United States Patent Office

Des. 216,969
Patented Mar. 24, 1970

216,969

VEHICLE SEAT

Chester J. Barecki, Grand Rapids, Mich., assignor to
American Seating Company, Grand Rapids, Mich., a
corporation of Delaware

Filed Apr. 8, 1969, Ser. No. 16,620

Term of patent 14 years

Int. Cl. D6—03

U.S. Cl. D15—8

FIGURE 1 is a front perspective view of a vehicle seat showing my new design; and

FIGURE 2 is a rear perspective view of the vehicle seat.

The side of the seat portion not shown is a mirror image of the side shown.

I claim:

The ornamental design for a vehicle seat, as shown and described.
